UNITED STATES PATENT OFFICE

163,993

WOODWIND MUSICAL INSTRUMENT

Edwin Eash, Elkhart, Ind.

Application April 1, 1950, Serial No. 8,904

Term of patent 14 years

(Cl. D56—1)

To all whom it may concern:

Be it known that I, Edwin Eash, a citizen of the United States, residing at Elkhart, county of Elkhart, and State of Indiana, have invented a new, original, and ornamental Design for a Woodwind Musical Instrument of which the following is a specification, reference being had to the accompanying drawing, forming a part thereof, in which:

Figure 1 is a side elevation of a woodwind musical instrument showing my new design;

Figure 2 is a perspective view of the uppermost key shown in Figure 1;

Figure 3 is a perspective view of the second key from the top in Figure 1;

Figure 4 is a perspective view of the third key from the top in Figure 1;

Figure 5 is a perspective view of the fourth key from the top in Figure 1;

Figure 6 is a perspective view of the fifth key from the top in Figure 1; and

Figure 7 is a perspective view of the bottom key in Figure 1.

The characteristic feature of the design resides in the portion shown in full lines on the drawing.

I claim:

The ornamental design for a woodwind musical instrument, as shown and described.

EDWIN EASH.
